UNITED STATES PATENT OFFICE

ERIK W. JOHNSON, OF CHICAGO, ILLINOIS, ASSIGNOR OF ONE-HALF TO LEON A. KAMRADT, OF CHICAGO, ILLINOIS

MEANS FOR CASTING TYPE FURNITURE BY TYPOGRAPHICAL MACHINES AND SIMILAR MACHINES

Application filed November 19, 1928. Serial No. 320,331.

This invention relates to new and improved means and methods of casting type furniture on intertype, linotype and similar machines.

The apparatus embodying the present invention is designed and adapted for casting type furniture from one em pica upward to forty-two ems picas when applied to type casting machines as above designated, having a melting pot arranged and positioned to inject molten metal into a slotted mold and against an intermediate plate or closure, which latter is slidably secured on means known to the art as a vise, whereby a type bar or slug may be produced. The molds referred to are usually constructed in a manner to provide slots or cavities having side walls, a bottom or body portion and an upper or cap portion, while the end walls are formed by two end portions of the cap-core, so called.

In the manufacture of the mold parts which are made of steel it is essential to harden the metal or at least that portion which forms the mold cavity in order to avoid both the adherence of the mold and metal within the surface of the cavity and also to resist wear and distortion therein during the ejection of the cast slugs as the latter are ejected from the mold in the usual way.

My invention contemplates the production of a uniformly satisfactory product; i. e. type furniture having the desirable characteristics of lightness, strength and durability to wear. The mold body comprising an important feature of my invention has a combination cap-core and a body portion so constructed as to resist warping, bending, buckling and breaking, to the highest degree, during the casting or ejecting operation, it having been found in actual practice that cores are comparatively frequently rendered defective during the casting and ejecting process, both by crystallization and stresses developed during the actual casting of the slugs.

Additional advantages and objects of my invention will appear more fully in the hereinafter specification when taken in connec-

tion with the accompanying drawings in which,

Figure 1 is a partial plan view of a linotype machine to which an embodiment of my invention is operatively applied.

Figure 2 is a face view of a novel intermediate plate forming a part of my invention, as applied to the vise of a linotype machine, taken on line 2-2 of Fig. 1.

Figure 3 is a face view of a mold-disk and disk-pinion, showing the molds forming a component part of my invention applied to the mold-disk, taken on line 3-3 of Fig. 1.

Figure 4 is a transverse section taken on line 4-4 of Figure 1, parts being broken away.

Figure 5 is a rear perspective view of a slug produced with the apparatus comprising my invention.

Figure 6 is a front elevational view of a mold produced in conformity with the object of my invention.

Figure 7 is a rear view of the mold shown in Figure 6.

Figure 8 is a top plan view of the mold as viewed from the rear side thereof.

Figure 9 is a cross-sectional view taken on line 9-9 of Figure 7.

Figure 10 is a cross section taken on line 10-10 of Figure 6.

In the drawings wherein similar characters of reference indicate corresponding parts in the several views, 15 designates the usual body portion of a mold having lugs or extensions 16, aligning studs or pins 17, and diagonally positioned screw holes 18 which register with corresponding screw holes 19, in the cap-core 20, the screw holes 19 being recessed to provide seats or shoulder portions 21, for the heads 22, of the machine screw bolts 23.

An integral cap-core is provided with notches 24, an upper longitudinal slot 25, a lower longitudinal slot 26 whereby a cavity 27 is formed, the bottom wall of which constitutes the upper surface of the mold body 15. In the space or cavity 27 are risers 28, the notches 24, and upper and lower slots 25, 26 respectively;—the notches and the lower slot serving to admit molten metal injected

under pressure from the linotype or intertype machine, whereby type furniture may be cast of a configuration corresponding to the contour of the cavity 27.

5 The cavity 27 of the mold is tapered or beveled transversely while the notches 24 are also tapered from front to rear, as shown in Figures 6 and 7. By reason of this construction, when molten metal is injected into the 10 cavity, the notches will form transverse strong supports or bridges 28' between the two opposite sides of "furniture" cast, with cells 29 running from top to bottom of the slug so formed, as best shown in Figure 5.

15 As an important feature of my invention and as best shown in Figures 1 and 2, I provide an intermediate sliding vise-plate or closure 30 which is supported on the left hand vise-jaw 31 of the slug casting machine by 20 means of an L-shaped clamping extension 32 fastened to the closure and provided with a ball 33, impelled by a spring 34, seated on a pin 35, in a passageway 36,—the spring impelled ball serving to maintain the closure in 25 firm position while accomplishing its functions as a stop or closure at the face of the mold during the process of slug casting. When a slug is to be cast, a downwardly extending L-shaped member 37 on the closure 30 projects over the right hand vice-jaw 38 and rests against the banking block 39 of the slug casting machine, in this manner eliminating a special bank block which would otherwise be required to take up the difference 35 in height of the mold when the slug is ejected. When molten metal under pressure is applied to the rear face of the cap-core 20, the metal will flow through the notches 24 and the lower slot 26, filling the upper slot 25 and the 40 entire cavity 27. When the cavity is filled, the molten metal will abut against the intermediate plate or closure, a uniformly accurate sharply defined strong slug being produced with the bridges or supports extending 45 from the top to the bottom as described above. My closure plate which is approximately one-eighth of an inch in thickness makes up the difference in the height of the standard mold, this being provided for in my invention as 50 my novel low mold is about one-eighth of an inch lower in height than the standard mold, the closure forming a part of this invention being interchangeable to linotype or intertype machines,—a feature of great practical 55 advantage.

As best shown in Figures 9 and 10, I provide special means to enable the operator of the slug-casting machine to remove and substitute one cap-core for another without the necessity, as hitherto was the case, of taking off or unscrewing the mold body from the mold-disk. The specific means for accomplishing this desirable convenience, which results in a substantial saving of time and labor in actual practice, consists in providing

the cap-core 20 and mold body 15 with diagonally positioned registering screw holes 18 and 19 respectively, with the coacting screw bolts 23 threaded therein and seated on the shouldered portion 21 of the screw holes 19,—this construction allowing the placing and removal of the screw bolts at an angle and consequently the removal of the cap-core, while allowing the mold body 15 to remain clamped in position on the mold-disk. The 70 aligning of the cap-core and the mold body, is obtained by means of fixed studs or pins 17 which are fastened to the mold body 15 in any suitable way, such as by a drive fit, the studs or pins 17 entering the notches 40 provided on the cap-core 20, thereby bringing the cap-core and mold body into alignment longitudinally and transversely.

With the mold and means described above I am able to cast printer's slugs known to the art as head letter or type slugs in addition to "furniture" by raising the height of the standard mold and then cutting down proportionately the risers or teeth 28 which form the cells 29 of the slugs.

In order to better comprehend the construction and mode of operation of my invention, those parts of the assembly of a slug-casting machine to which the apparatus embodying my invention is immediately applied, and as illustrated in Figures 1, 2, 3 and 4, will be described briefly:

The left hand vise jaw 31, is slidably mounted on the vise jaw table frame 41, by means of a shoe 60, which has a vertical rail 61, in a groove 62 of the vise-cap 42, as best shown in Figure 4. It will now be readily understood that the L-shaped member 32 of the intermediate vise plate 30 is slidably seated on the shoe 60.

To remove the intermediate plate 30, the operating screw handles 47 are turned in a counter-clockwise direction, thereby unlocking the vise jaw 41 from the linotype machine, the jaw swinging towards the operator.

Located on the upper surface of the cap 42, is a slot 63, wherein is positioned an adjusting bar 48, which at one end has the usual finger operating lug, and is at the other end secured to bracket 53. In the bracket 53 is the justification rod 54, which is normally held in position by the left hand wedge bracket 51, which is secured to the frame 41. The justification rod 54 at its outer end abuts against the left hand vise jaw 31. The rod 54 is locked by a post 50, which latter is lifted into and out of engagement by means of the bar 52 spring held, and secured by means of screws 64.

Mounted on the upper surface of the bar 48 is an operating bar 49, one end being provided with the usual finger lug, and the other end with a tension spring which serves to normally hold the bar 49 closed. In oper-

ation the bar 49 is moved to the right, thereby raising the bar 52 and post 50 out of engagement with the justification rod 54. The bars 48 and 49 are moved to the left, carrying rod 54 to the left away from the left hand vise jaw member 31, the latter being moved by the hand to the left readily permitting the intermediate plate 30 to be removed.

By referring to Figure 3, it will be seen that the mold disk 55 which is of the conventional type, is provided with the usual pockets 56 and the shoulders 56', which latter serve as seats for the special lugs 16 forming a part of my invention, the pockets 56 accommodating the cap-core and mold body. For the operation of the mold disk, the usual mold disk pinion 57 is provided. By inspection of the mold disk 55, it will be seen that the mold body 15 is bolted to the disk by the usual bolts 66. Hitherto, as pointed out above, it was necessary when substituting one mold for another to remove both cap and core and the mold body. By the means above described and illustrated in the drawings, the cap and core may now be quickly removed by merely unscrewing the machine bolts 23, thereby permitting the immediate substitution of another cap-core.

While I have described with some degree of particularity a preferred construction and arrangement of the various parts, it will be understood that the apparatus is susceptible of modification and variation; hence I do not wish to be limited to the precise details as set forth, but desire to avail myself of such changes and embodiments as fairly lie within the scope of the appended claims.

What I claim is new and desire to secure by Letters Patent is:

40 1. A slug casting mold comprising a lower and an upper section, said lower section consisting of a mold body having a plurality of obliquely positioned threaded apertures, the upper section having a plurality of risers fore-
45 shortened to provide stronger walls in slugs formed therewith, said risers being longitudinally situated on the underneath side of said upper section, an upper slot separating the main body portion of said risers from the
50 top portion of the upper section, a plurality of notches separating the risers and communicating with said upper slot, a plurality of obliquely positioned threaded apertures in the upper section registering with the apertures in the lower section, and means within the registering apertures to couple the upper and lower sections together.

2. In a slug casting device, in combination, a mold and a one piece member serving both as a closure for said mold and as a banking plate.

3. A slug casting mold with a front closure, said closure being interchangeable to intertype and linotype machines and detachably secured to the movable vise jaws for option-

ally producing standard 30 ems picas and 40 ems picas.

4. A slug casting device for closing the flow of metal at the front of the mold, said device consisting, in combination, of a one piece closure member adapted to cooperate with said mold and with a banking block.

5. A mold consisting of a unit interchangeable from one machine to the other such as intertype and linotype, said mold having two ends projecting out for optional engagement with the mold disk wheels on said intertype and linotype machines.

6. A slug casting mold comprising a mold body, a combined cap and core detachable from the mold body, said combined cap and core having a plurality of fore-shortened tapered risers within the cavity formed by the joining of the cap and core to the mold body, said fore-shortened tapered risers being especially adapted to provide stronger walls in the slugs formed by furniture casting molds.

7. An integral cap-core having upper and lower longitudinal slots, a plurality of notches communicating with said longitudinal slots, a plurality of fore-shortened tapered risers individually separated by the slots and notches, said risers being especially adapted to resist crystallization and breakage during use.

8. In a mold of the character described, in combination with a vise jaw, a mold body including a combined cap and core secured to said mold body by diagonally positioned elements received in registering holes formed in the mold body and in the cap and core, and a removable coacting closure element interposed slidably between the mold and vise jaw and being yieldingly pressed against said vise jaw.

9. In a mold of the character described, in combination with a vise jaw, a combined cap and core detachably connected to a mold body by a plurality of bolts secured in diagonally positioned registering apertures formed in said mold body and said cap and core, and a closure element resiliently held in position against the vise jaw in working relation to said mold.

10. In a mold of the kind described, in combination with a vise jaw, a mold body cooperating with a combined integral cap and core unit to provide a cavity with upper and lower longitudinal slots lying on the top and bottom sides of tapered risers therein, a plurality of notches communicating with said cavity from the rear, and a closure for the front of the cavity resiliently held against said vise jaw and by the latter against the mold.

11. In a mold of the character described, in combination with a vise jaw, a mold body cooperating with a combined cap and core to provide a channel extending from front to

back of said mold body and cap and core, and a removable closure for said channel resiliently maintained in position against said vise jaw.

- 5 12. A cored slug casting mold comprising a mold body in combination with a vise jaw, a cap-core detachable from said mold body, said cap-core having upper and lower longitudinal slots extending from one end to the
10 other thereof adapted to form the upper and lower side walls of the slugs, the side walls of said cap-core being cut down to provide more durable walls on a slug formed thereby, and a coacting closure element resiliently held against said vise jaw and by the latter against said mold.

- 15 13. A mold for casting type of hollow formation having reinforced bridges from top to bottom, said mold comprising a top and bottom section with a cavity formed between said top and bottom sections, and notches communicating with the cavity which has risers therein separated by slots, and a cooperating closure for said mold comprising an interposed plate movably held against a vise jaw in the direction from the mold and being supported by said jaw in closed working relation to said mold.

20 In testimony whereof I have signed my name to this specification.

ERIK W. JOHNSON.
